CLAIM

The ornamental design for an in line smart print module, as shown and described.

DESCRIPTION

FIG. 1 is a front left perspective view of an in line smart print module illustrating our new design, the back is not part of the claimed design;

FIG. 2 is a front right perspective view of thereof;

FIG. 3 is a front elevation view thereof;

FIG. 4 is a top rear view thereof;

FIG. 5 is a front right perspective view of a second embodiment of an in line smart print module illustrating our new design, the back is not part of the claimed design; and,

FIG. 6 is a rear left perspective view thereof.
